[57] CLAIM

The ornamental design for a nozzle, as shown and described.

DESCRIPTION

FIG. 1 shows a perspective view of the nozzle;

FIG. 2 shows a front view of the nozzle; and,

FIG. 3 shows a side view of the nozzle, the other side view
being a mirror image thereof.The nozzle of the present invention may be employed in
various contexts but advantageously may be employed in the
form of a nozzle insert in an actuator. The outline of a
representative actuator is shown in broken lines for illustrative
purposes only and forms no part of the claimed design.
